F. FARRELL

POWER DRIVEN BUTCHER SAW

Filed March 8, 1926

UNITED STATES PATENT OFFICE.

FRED FARRELL, OF SACRAMENTO, CALIFORNIA.

POWER-DRIVEN BUTCHER SAW.

Application filed March 8, 1926. Serial No. 93,030.

This invention relates to improvements in saws and particularly to meat and bone cutting saws such as are used by butchers.

The principal object of my invention is to provide a hand saw, that is one to be entirely supported and guided by the human hand, having a self-contained power mechanism for operating the blade of the saw.

The construction is such that the operator need only hold and guide the saw frame in place and exert the necessary downward pressure on the same, and does not have to move the arm back and forth to obtain the cutting action, as is the case with the usual hand saw.

There are certain power saws already on the market for butchers' use, but as far as I am aware, these are all large and non-portable devices, not suitable nor intended to be used in cutting individual steaks, chops and the like. My saw on the other hand is a small portable structure which may be used by the individual butchers wherever they happen to be located, for any operations where the present hand saws are used.

A further object of the invention is to produce a simple and inexpensive device and yet one which will be exceedingly effective for the purpose for which it is designed.

These objects I accomplish by means of such structure and relative arrangement of parts as will fully appear by a perusal of the following specification and claims.

Fig. 1 is a side elevation of my improved saw. Fig. 2 is a vertical section on the line 2—2 of Fig. 1.

Referring now more particularly to the characters of reference on the drawings, the numeral 1 denotes the main frame, formed with downwardly depending arms 2, one at one end and the other intermediate the ends of the frame, and with another similarly disposed arm 3 at the other end.

Bearing sleeves 4 are provided at the ends of the arms 2, in which sleeves are slidably mounted opposed and aligned stems or shafts 5 which project rigidly from the ends of an auxiliary arch frame 6 which is transversely aligned with the frame 1 and disposed between the arms 2. The length of the frame 6 is sufficiently less than the distance between said arms to allow of a predetermined longitudinal travel of the frame 6 relative to the frame 1.

Lugs 7 facing each other are provided on

the ends of the frame 6, from which lugs pins 8 project laterally to engage and support an ordinary form of hack-saw blade 9. The lug adjacent the outermost arm 2 is in the form of a stem longitudinally slidable 60 in the adjacent stem 5, with a take-up means 10 to come from therebetween, to enable the tension of the blade to be altered at will.

Between the inner arm 2 and the arm 3 a bevel gear 11 is disposed. The central shaft 65 12 of this gear is disposed horizontally and transversely of the frame 1 and is horizontally aligned with the stems 5, being supported by an arm 13 depending from the frame 1. A slotted cross-head 14 is fixed on the adjacent stem 5 and extends alongside the gear 11. A block 15 is slidable in the cross-head, said block being fixed on a crank pin 16 mounted on the gear.

The gear meshes with a pinion 17 whose 75 shaft is mounted in a sleeve 18 provided on the lower end of the arm 3. A small electric motor 19 whose shaft is aligned with and connected to the pinion shaft is secured to the arm 3 outside the same. A handle 20 80 through which the flexible current conducting cable 21 to the motor passes, projects longitudinally from the motor.

In operation it will be seen that with the driving of the motor the frame 6 and blade 9 are reciprocated through a distance governed by the throw of the crank pin 16, thus imparting the necessary sawing action to the blade. With this operation the frame 1, which is supported and maintained in the 90 necessary position by the operator gripping the handle 20, remains stationary relative to the saw blade.

The axis of the motor and the handle are preferably in transverse alignment with the 95 stems 5, so as to provide the proper lateral balance for the tool and enable the operator to easily support the tool in the desired position relative to the material being cut with a minimum of effort.

From the foregoing description it will be readily seen that I have produced such a device as substantially fulfills the objects of the invention as set forth herein.

While this specification sets forth in detail 105 the present and preferred construction of the device, still in practice such deviations from such detail may be resorted to as do not form a departure from the spirit of the invention, as defined by the appended claims.

Having thus described my invention what I claim as new and useful and desire to secure by Letters Patent is:

1. A power saw comprising a main frame, an auxiliary frame transversely aligned with the main frame, longitudinally aligned stems projecting from the ends of the auxiliary frame and slidable in the main frame, means mounted in connection with the stems for supporting a saw in longitudinal alinement with the stems, a motor axially aligned with the stems mounted on the main frame beyond the auxiliary frame, a slotted crosshead mounted on the adjacent stem, the slot of said crosshead being at an angle to the stem, a gear driven from the motor mounted on the main frame and to one side of the crosshead in a plane parallel thereto, and a block turnably mounted on the gear eccentric to the axis thereof and riding in the slot to im-
2. A power saw comprising a main frame, an auxiliary frame transversely aligned with the main frame and arranged for longitudinal movement relative thereto, longitudinally aligned stems projecting from the ends of the auxiliary frame, bearing means on the main frame in which said stems are slidable, means applied to one stem for reciprocating the auxiliary frame, another stem slidable in the other stem of the auxiliary frame, take-up means between the cooperating stems, and means on said slidable stem and on the opposite end of the auxiliary frame for supporting a saw.

In testimony whereof I affix my signature.

FRED FARRELL.
